FURNACE BOTTOM SUPPORTS

Frank J. Boron, Elyria, Ohio, assignor to American Brake Shoe Company, New York, N. Y., a corporation of Delaware

Application December 19, 1955, Serial No. 554,075

4 Claims. (Cl. 263—40)

This invention relates to work-container supports for heat treating furnaces of the well known forced convection type.

In many furnaces of the foregoing kind, a fan or such forced draft means is mounted at the bottom of the furnace beneath the basket or work-container carrying the work to be heated, so that the furnace atmosphere is forcibly directed upwardly through and about the work-container to heat the work. It has been proposed to dispose between such forced draft means and the work-container a so-called bottom support on which the container is rested and which affords a housing in which the forced draft means operates beneath the lower open end of the work-container. Such bottom support has been furnished in the form of a one-piece part, either a unitary casting or segments that are welded to afford a full circle bottom support, and it has been found that these have a relatively short life due to the rather severe thermal expansions that are encountered.

The primary object of the present invention is to increase the life of the bottom support of a furnace by constructing the bottom support of two complementary half castings connected in such a way that these complementary parts can expand and contract freely, and to facilitate this by assuring that certain connecting joints between the half castings do not carry any of the load of the work container. Specifically, the object of the invention is to provide ears at the opposed ends of the half castings that afford loose joint connections between the half castings so as to unite these while allowing thermal expansion or creep to occur freely.

Other and further objects of the present invention will be apparent from the following description and claims and are illustrated in the accompanying drawings which, by way of illustration, show a preferred embodiment of the present invention and the principles thereof and what I now consider to be the best mode in which I have contemplated applying that principle. Other embodiments of the invention embodying the same or equivalent principles may be used and structural changes may be made as desired by those skilled in the art without departing from the present invention and the purview of the appended claims.

In the drawings:

Fig. 1 is a top plan view of a furnace bottom support constructed in accordance with the present invention;

Fig. 2 is a sectional view taken substantially on the line 2—2 of Fig. 1;

Fig. 3 is a top plan view of a half casting; and

Fig. 4 is a side elevation of the half casting shown in Fig. 3.

The present invention is illustrated in Fig. 1 as embodied in a furnace bottom support 10 that comprises two complementary half castings 10A and 10B which at opposite ends are connected together so as to compensate for thermal expansion in a way to be described more specifically hereinbelow.

The bottom support in the present instance is adapted

2

to be used in a heat treating furnace such as the kind illustrated in U. S. Patent No. 2,686,665, so that the furnace bottom support 10 comprises a work-container support defined in part in the present instance by an upper wall or flange afforded by complementary 180° half-circle wall segments 12A and 12B corresponding to the respective half castings 10A and 10B. It will be observed in Fig. 1 that the fully complemented upper wall thus afforded defines an opening 15 of relatively large diameter, but of somewhat smaller diameter than the bottom of the work-container or basket that is adapted to be supported by the complementary upper wall segments 12A and 12B.

Spaced from the upper wall of the bottom support 10 is an annular or full-circle lower wall defined by complementary 180° half circle wall segments 18A and 18B. The wall segments 12A, 18A and 12B, 18B are integrally united by corresponding half-circle vertical web sections 20A and 20B so as to provide a chamber for gases below 20 the work-container.

The lower wall afforded by the wall segments 18A and 18B extends radially inwardly of the opening 15 in the upper wall, and the rounded inner edges thereof form a lower wall opening 23 which is of substantially less diameter than the diameter of a fan that is adapted to be mounted below the lower wall. Preferably, reinforcing ribs 25 are cast integral with the half castings so as to extend between the respective upper and lower wall segments as shown in Fig. 2.

In the furnace, a fan is arranged below the bottom support 10 with the shaft thereof directed upwardly so that the fan blades rotate in a horizontal path beneath the lower wall segments 18A and 18B. The fan thus rotates within a housing or chamber afforded by four helically disposed vanes as 26, there being two such vanes dependent from the respective half castings 10A and 10B in regular circumferential spacing. The vanes are cast integral with the two half castings so as to depend from the respective lower walls 18A and 18B. In this connection, it will be observed that the arrangement of the vanes is such that the inner ends 27, Figs. 1 and 2, terminate at points on the circumference of the opening 15 in the upper wall of the bottom support, and flare outwardly on diverging arcs so that the outer ends 28 thereof

are radially outwardly of the respective webs 20A and 20B. The inner ends 27 of the vanes 26 are on a circle that is somewhat larger than the path of the fan blades, and the lower edges 30 of the respective vanes are adapted to serve as standards reposing on the upper 50 face of a base member of the furnace such as illustrated in the aforesaid patent.

It is advantageous to prevent debris or particles of the material undergoing heat treatment from entering the circular fan housing afforded by the vanes 26, and 55 to this end gusset-like guards 33 and 34 are provided so as to extend horizontally between the webs 20A and 20B and the upper edges of the vanes 26 that are outwardly of the webs 20A and 20B as shown particularly in Fig. 1. To assist in centering the work container on the flange 60 or upper wall of the work support 10, vertical lugs 35 are provided outwardly of the webs 20A and 20B. These are preferably located at points where the guards 33 and 34 are joined to the webs 20A and 20B.

As shown in Fig. 1, there is substantial circumferential 65 spacing between the outer edge 28 of one vane and the inner edge 27 of the next adjacent vane, and it will be further observed that the respective ends of the half castings terminate at two such areas, which is to say that the end portion of one half casting extends slightly in a 70 forward direction beyond the outer end 28 of the associated vane 26 while the adjacent end portion of the

other half casting extends somewhat rearwardly beyond the inner end 27 of its associated vane 26. The half casting thus having the end portion extended forwardly beyond the outer end of the associated vane is provided with an ear 40 which, as shown particularly in Figs. 2 and 4, is off-set upwardly and then forwardly in a horizontal plane so as to overlap and rest on the flat, free end portion 41, Fig. 2, of the adjacent half casting. Such constitutes an expandable joint, and normally there is slight spacing between the respective ends 43 and 44 of the two half castings as shown in Fig. 1.

To connect loosely the half castings together so that the ears 40 provided on opposed ends of the respective half castings overlap the free end portion as 41 of the adjacent half casting, off set ears are also afforded on the webs 20A and 20B. Thus, as shown particularly in Figs. 1 and 3, ears 46 are off set radially outwardly and then forwardly from ends of the webs 20A and 20B corresponding to the ears 40, and the arrangement is such that these ears 46 overlap the flat, free end portion of the adjacent end of the opposite web 20A or 20B. In the present instance, pairs of fastening bolts as 47 having associated nuts and washers are passed through pairs of aligned openings in each ear 46 and the portion of the web of the opposite half casting that is behind the ear 46. Such openings are indicated at 50 in the ears 46, Figs. 3 and 4 and at 51 at the opposite, flat end of the web 20A, and are slightly larger in diameter than the shank of the bolts so that the half castings are enabled to creep or expand thermally to the full extent as defined by the predetermined spacing between the aforesaid ends 43 and 44 of the half castings.

Of particular importance in the present instance is that the ears 40 are provided at areas where there is circumferential spacing between the adjacent ends of adjacent webs 26 as was mentioned above. This assures that the joint afforded by the ear 40 and the underlying flat end portion of the lower wall segment of the opposite half-casting does not carry any of the load that is carried by the vanes 26 reposing on the support of the bottom of the furnace as was mentioned above. This particular arrangement frees the ears 40 of any vertical thrust so that thermal expansion occurs without resistance.

Hence, while I have illustrated and described the preferred embodiment of my invention, it is to be understood that this is capable of variation and modification, and I therefore do not wish to be limited to the precise details set forth, but desire to avail myself of such changes and alterations as fall within the purview of the following claims.

I claim.

1. In a bottom support for a furnace having adjacent its base a fan for forcibly circulating heated gases upwardly through and about an open-bottomed work-container in the furnace, two 180° complemental half castings adapted to be connected at ends thereof to provide a fan housing and a support for said container, each such casting comprising, a half-circle upper wall segment so that when the castings are connected such segments cooperate at their respective ends to afford a full-circle upper wall having an opening therein and on which said container is adapted to be supported over said opening, a half-circle lower wall segment so that when the castings are connected such lower wall segments cooperate at their respective ends to afford a full circle lower wall having an opening therein, said lower wall segments being joined to their respective upper wall segments by vertical spacing webs thereby affording an intervening chamber for circulation of gas below the bottom of said container, an ear off-set vertically and then forwardly at selected opposed ends of the lower wall segments of said half castings so as to overlap adjacent flat end portions of the lower wall segments with spacing between such opposing ends of the lower wall segments allowing for thermal

expansion, spaced vanes depending from each lower wall segment so as to define a 360° fan housing and afford a standard for said bottom support in the furnace, said vanes diverging from their inner ends radially outwardly and terminating in outer ends disposed outwardly of said webs, the ends of the lower wall segments having ears and the ends of the lower wall segments having flat portions being located between the inner and outer ends of immediately adjacent vanes so that the ears and said overlapped flat portions carry none of the load of the work-container and are free to allow expansion as aforesaid, an ear off-set radially and then forwardly from selected opposed ends of the webs in said half castings so as to overlap an adjacent flat end portion of the webs, and means loosely connecting each radially off-set ear and the overlapped web portion corresponding thereto.

2. In a bottom support for a furnace having adjacent its base a fan for forcibly circulating heated gases upwardly through and about an open-bottomed work-container in the furnace, two 180° complemental half castings adapted to be connected at ends thereof to provide a fan housing and a support for said container and each comprising, a half-circle upper wall segment so that when the two castings are connected such upper wall segments cooperate at their respective ends to afford a full-circle upper wall having an opening therein and on which said container is adapted to be supported over said opening, a half circle lower wall segment so that when the castings are connected such lower wall segments cooperate at their respective ends to afford a full circle lower wall having an opening therein, said lower wall segments being joined to their respective upper wall segments by vertical spacing webs thereby affording an intervening chamber for circulation of gas below the bottom of said container, an ear off-set vertically and forwardly at selected ends of the lower wall segments of said half castings so as to overlap adjacent flat end portions of the lower wall segments with spacing normally between such opposing ends of the lower wall segments allowing for thermal expansion, spaced vanes depending from each lower wall segment so as to define a fan housing and afford a standard for said bottom support in the furnace, said vanes having inner ends inwardly of said webs and outer ends disposed outwardly of said webs, the ends of the lower wall segments having ears and the ends of the lower wall segments having flat portions being located between the respective inner and outer ends of a pair of immediately adjacent vanes so that the ears and said flat portions carry none of the load of the work-container and are free to allow expansion as aforesaid, and means loosely connecting said castings at ends thereof.

3. In a bottom support for a furnace having adjacent its base means for forcibly circulating heated gases upwardly through an open-bottomed work-container in the furnace, two complemental half castings adapted to be connected at ends thereof to provide a chamber for such gases below the work-container and a support for said container above said chamber, each such casting comprising, an upper wall half segment so that when the castings are connected such segments cooperate at their respective ends to afford a fully complemented upper wall on which said container is adapted to be supported, a lower wall half segment so that when the castings are connected such lower wall segments cooperate at their respective ends to afford a fully complemented lower wall, said lower wall segments being joined to their respective upper wall segments thereby affording an intervening chamber for circulation of gas below the bottom of said container, an ear off-set vertically and then forwardly at selected ends of the lower wall segments of said half casting so as to overlap adjacent flat end portions of the lower wall segments with spacing between such opposing ends of the lower wall segments allowing for thermal expansion, and means depending from each lower wall segment so as to afford a standard for said bottom support in the

furnace except at the aforesaid opposing ends so that said ears and the associated overlapped portions do not carry any of the load of said work-container.

4. In a bottom support for a furnace having adjacent its base means for forcibly circulating heated gases upwardly through and about an open-bottomed work-container in the furnace, two complemental half castings adapted to be connected at ends thereof to provide a chamber for such gases below the work-container and a support for said container above said chamber, each such casting comprising, an upper wall half segment so that when the castings are connected such segments cooperate at their respective ends to afford a fully complemented upper wall on which said container is adapted to be supported, a lower wall half segment so that when the castings are connected such lower wall half segments cooperate at their respective ends to afford a fully complemented lower wall, said lower wall segments being joined to their respective upper wall segments by vertical spacing webs thereby affording an intervening chamber for circulation

15

20

of gas below the bottom of said container, an ear off-set vertically and then forwardly at selected ends of the lower wall segments of said half castings so as to overlap adjacent flat end portions of the lower wall segments with spacing between such opposing ends of the lower wall segments allowing for thermal expansion, means depending from each lower wall segment so as to afford a standard for said bottom support in the furnace except at the aforesaid opposing ends so that said ears and the associated overlapped portions do not carry any of the load of said work-container, and means loosely connecting respective spacing webs of said half castings at ends thereof.
